UNITED STATES PATENT OFFICE

2,283,024

AIR CONDITIONING APPARATUS

Edward R. Wolfert, Springfield, Mass., assignor to Westinghouse Electric & Manufacturing Company, East Pittsburgh, Pa., a corporation of Pennsylvania

Application December 1, 1938, Serial No. 243,410

1 Claim. (Cl. 230—206)

My invention relates to a motor-compressor unit for a refrigerating system, more particularly to a unit enclosed in a fluid-tight casing and wherein the motor is cooled by the expanded refrigerant vapor flowing to the compressor, and it has for an object to provide an improved unit of the character set forth.

A more particular object is to provide an improved arrangement for separating oil from the expanded refrigerant vapor before the same enters the compressor cylinders.

In accordance with my invention, the motor housing, through which the expanded refrigerant vapor flows in contact with the motor for cooling the same, is formed to provide sufficient change in direction of flow and sufficiently low velocity to permit the lubricant entrained in the refrigerant vapor to separate therefrom by gravity, so that the motor housing serves as an oil separator. In the horizontal unit, the motor housing is formed with a vapor outlet which is located, preferably at the top of the motor housing and remote from the vapor inlet, so as to receive refrigerant vapor from which the oil has been separated. The refrigerant vapor is then admitted to the compressor cylinders.

These and other objects are effected by my invention as will be apparent from the following description and claims taken in connection with the accompanying drawings forming a part of this application, in which:

Fig. 1 shows diagrammatically a refrigerating system incorporating a horizontal motor-compressor unit in accordance with my invention, the unit being shown in vertical section;

Fig. 2 is a broken perspective view showing the refrigerant vapor passage from the motor housing to the compressor cylinders;

Fig. 3 is an end view of the motor with the end cover plate removed, as seen on the line III—III of Fig. 1; and

Fig. 4 is a perspective view of a similar motor-compressor unit having a greater number of cylinders.

Referring to the drawings in detail, the motor-compressor unit indicated generally by the reference numeral 10, is part of a refrigerating system which includes, in addition to said unit, a discharge conduit 11, a condenser 12 which also serves as a liquid receiver, an expansion valve 13, an evaporator 14 and a suction conduit 15. The expansion valve 13 may be of any suitable type known in the art, such as a thermostatic expansion valve which regulates the flow to

maintain a constant degree of superheat of the refrigerant vapor leaving the evaporator.

The refrigerating system as a whole operates in the usual manner of such apparatus, the refrigerant gas compressed by the motor-compressor unit 10 being conveyed through the discharge conduit 11 to the condenser 12, wherein the same is condensed. The liquefied refrigerant then flows to the evaporator 14 through the expansion valve 13, which regulates the flow and also reduces the pressure thereof. In the evaporator 14, the liquid refrigerant is vaporized by heat extracted from the substance to be cooled by the evaporator and the vaporized refrigerant flows through the suction conduit 15 to the motor-compressor unit, wherein the same is re-compressed and recirculated.

The motor compressor unit 10 includes a compressor 16 and a motor 17. The compressor and 20 the motor are enclosed in a fluid-tight casing 18 which comprises a main frame or casing member 19, end cover plates 21 and 22 and a cylinder head 23. The fluid-tight casing 18 is divided by a partition 24 into a compressor housing and a 25 motor housing. Compressor cylinders 25 are formed in the compressor portion of the main frame or casing member 19, and pistons 26 movable therein are connected through connecting rods 27 to a crankshaft 28. The latter is journaled in bearings 29 and 30 carried by the cover plate 21 and the partition 24, respectively.

Below the cylinders 25, the compressor housing forms a crank case 31, the lower portion of which constitutes an oil or lubricant reservoir. 35 The body of oil extends into the motor housing, the partition 24 being formed with an opening 32 extending below and above the surface of the body of oil. An oil pump 33 is driven by the crankshaft through gears 34 and has its inlet 40 submerged in the oil. It discharges oil through suitable passages to the several bearing surfaces, as is well known in the art.

The motor 17 includes a rotor 35 mounted on an overhung portion 36 of the crankshaft 28. 45 The motor 35 is formed with axially-extending passages 37 for flow of expanded refrigerant vapor therethrough to cool the rotor. The motor further includes a stator 38, which is pressed into the cylindrical inner surface of the motor housing, the latter serving as a frame for the motor. The stator 38 is formed to provide passages 39 between the same and the motor housing for flow of refrigerant to cool the stator. These passages may be provided by forming the stator as shown in Fig. 3, the stator being provided

with cylindrical surfaces 41 which contact the motor housing and with flat surfaces 42 which provide the passages 39.

The end cover plate 22 is formed with a vapor inlet 43 connected to the suction conduit 15. A strainer 44 may be provided at the inlet as shown.

The casing member 19 is formed to provide a vapor outlet 45 for the motor housing at the compressor end thereof. As shown in Fig. 2, the outlet 45 is disposed adjacent the top of the motor housing and on one side of the unit. The casing member 19 is further formed to provide a passage 46 for flow of refrigerant vapor from the outlet 45 to the compressor cylinders. The passage 46 comprises a portion 47 extending horizontally from the outlet 45 and a portion 48 extending vertically along the pair of cylinders. I prefer to provide one passage portion 48 for each pair of cylinders, and the horizontal portion 47 is of sufficient extent to communicate with all of the passage portions 48.

The motor-compressor unit shown in Fig. 4 has four cylinders, so that the horizontal portion 47 is of greater extent.

Each cylinder of the compressor is provided with inlet and discharge valves, the specific construction and arrangement of which forms no part of the present invention. By way of example, I show a valve cage 49 clamped between the cylinder head and the cylinder, and including an inlet valve portion 51 and an outlet valve portion 52. The expanded refrigerant vapor flows from the vertical passage portion 48 through a tubular connecting member 53, a suitable inlet chamber 54 in the cylinder head and the inlet valve portion 51 to the cylinder. The compressed refrigerant flows from the cylinder through the discharge valve portion 52, a suitable discharge passage or chamber 55 in the cylinder head, a tubular connecting portion 56, and other suitable passages (not shown) to the discharge conduit 11. For further description of the valve and cylinder head construction, reference is made to Patent No. 2,134,077 of Emil Ehret.

As will be noted particularly upon reference to Fig. 1, when the refrigerant vapor enters the motor housing from the inlet 43, the direction thereof is suddenly changed, and the velocity thereof is greatly reduced due to the relatively great amount of space or flow area in the end of the motor housing. Accordingly, the particles of oil or lubricant entrained in the refrigerant vapor have ample opportunity to separate by gravity and to drop to the body of liquid in

the bottom of the motor housing. The refrigerant vapor flows from the outer end of the motor housing to the compressor end through the passages 31 and 39 and the gap between the rotor and the stator, thereby cooling the rotor and the stator by direct contact therewith. As the refrigerant vapor leaves said passages and said gap and enters the compressor end of the motor housing, the direction of most of the refrigerant vapor is again changed and its velocity reduced, thereby providing further opportunity for separation by gravity of particles of entrained oil or lubricant. Accordingly, as the refrigerant vapor reaches the outlet 45, the oil has been effectively separated therefrom. The refrigerant vapor then flows to the several cylinders through the passage 46 as described above.

From the above description it will be seen that I have provided a motor compressor unit wherein the motor housing serves as an oil separating chamber, thereby dispensing with the necessity of providing a separate or additional oil separator.

What I claim is:

25 An enclosed motor and compressor unit for a refrigerating system comprising a compressor, a motor for driving the compressor, a common fluid-tight casing for the compressor and the motor, said casing including a crankcase for the compressor and a tubular housing for the motor extending horizontally from the crankcase and having an end wall at the end remote from the crankcase, a substantially vertical partition disposed between said crankcase and said motor housing, a shaft extending horizontally through said partition for connecting said motor and compressor, said motor embodying an armature carried by said shaft and a stator secured in said tubular housing of the casing structure, said stator and said rotor being so spaced from the end wall of the motor housing as to provide a refrigerant space of substantial volume to effect separation of lubricant by gravity from the refrigerant vapor, means provided on the portion 30 of said casing forming said refrigerant space for admitting vaporous refrigerant having lubricant entrained therein to said space, means provided in the lower portion of the casing for conveying lubricant separated from the refrigerant to the 35 crankcase, and passageway means provided in the casing above the oil therein for conveying refrigerant vapor from said refrigerant space axially through the motor to cool the same and thence to the inlet of the compressor.

CERTIFICATE OF CORRECTION.

Patent No. 2,283,024.

May 12, 1942.

EDWARD R. WOLFERT.

It is hereby certified that error appears in the printed specification of the above numbered patent requiring correction as follows: Page 1, second column, line 30, for "29 and 20" read --29 and 30--; page 2, second column, line 22-23, after the word and period "separator." insert the following paragraph -

-- While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims. --

and that the said Letters Patent should be read with this correction therein that the same may conform to the record of the case in the Patent Office.

Signed and sealed this 23rd day of June, A. D. 1942.

(Seal)

Henry Van Arsdale,
Acting Commissioner of Patents.
